HUMIDIFYING APPARATUS

Guy L. Briggs, St. Marys, Ohio

Application February 26, 1938, Serial No. 192,874

5 Claims. (Cl. 299—86)

My invention relates to humidifying apparatus and more particularly to a type for maintaining or raising the humidity of the atmospheric air in a room or the like.

5 One of the principal objects of my invention is to provide a humidifying apparatus wherein compressed air is mixed with water and discharged within a room or the like.

Another object of my invention is to provide 10 an apparatus of the class described whereby both the air and water are heated previous to being mixed and discharged within a room.

A further object of my invention is to provide means whereby a desired mixture of air and 15 water may be maintained during the operation of the apparatus.

A still further object of my invention is to provide an apparatus of the class described which is simple in construction, durable in use, efficient in operation and economical in manufacture.

Other objects and advantages will be apparent from the following description, appended claims and annexed drawing.

25 In practicing my invention I provide an air tank 5, the same being shown in vertical section in the annexed drawing, having mounted on the outside thereof an air compressor 6 operated by an electric motor 7 through a belt connection 8. Said motor is likewise mounted on the outside of the tank 5. A pipe line 9 connects the compressor 6 to the tank whereby air under pressure is introduced into the tank. The tank 5 is fashioned with a dome shaped top 10 provided with an outlet pipe 11 to which is secured a T connection 12. One of the outlets of said T connection has secured thereto a pressure gauge 13 for indicating the air pressure within the tank, and the other outlet has secured thereto one end of a discharge pipe 14, the opposite end of said discharge pipe having secured thereto a discharge nozzle 15. Secured to the discharge pipe 14 adjacent the nozzle 15 is a bracket 16 having the lower end connected to and supporting the upper end of a siphon tube 17. Said upper end of said siphon tube is positioned adjacent the discharge port of the nozzle 15 and in the path of air discharged therethrough. The lower end of the tube 17 is connected to the upper end of a heating coil 18 disposed within the upper section of the tank 5. The lower end of the heating coil extends without the tank and is positioned within the lower section and adjacent the bottom of a water receptacle 19. Said 55 receptacle is mounted on the opposite side of

the tank from the compressor 6. A water supply line 20 is connected to the lower section of the receptacle 19 adjacent the bottom thereof and supplies water within the receptacle. A float valve 21 is connected to the outlet port of the pipe 20 within the receptacle and controls the discharge of water therein.

The bottom of the tank 5 is open and the outer periphery fashioned with a circumferentially extending flange 22 connected to a base 23 having a top wall 24 and which serves to close the bottom of the tank. A gasket 25 is interposed between the flange 22 and top wall 24 for effectively sealing the bottom of the tank against leakage. Said tank is secured to said base by 15 means of bolts 26. Mounted on the top wall 24 of the base 23 is a detachable electric heating element 27 extending upwardly within the lower section of the tank, said heating element being connected to a suitable source of electrical energy 20 by means of wiring 28 as clearly illustrated in the drawing.

In operation, air is compressed within the tank by means of the compressor 6 and discharged therefrom through the pipes 11, 14 and 25 nozzle 15, the gauge 13 indicating the amount of pressure of the air. As the air is discharged out of the nozzle 15 it passes over the upper end of the siphon tube 17 thereby siphoning the water from the receptacle 19 upwardly through the 30 water heating coil 18 for mixture with the discharged air. During this operation, the heating element serves to heat both the air within the tank and the water within the heating coil 18, thus effecting a mixture of heated air and water 35 at the discharge point of the nozzle 15 in a manner that the heated air picks up the water and transforms the mixture into a very fine vapor and atomizes the same into a room or the like for maintaining or raising the humidity of 40 the atmospheric air therein. By means of the float valve 21, the amount of water discharged into the receptacle from the feed line 20 is regulated, thus in turn regulating the amount of 45 heated water mixed with the heated air discharged through the nozzle 15.

From the foregoing it will be apparent that I have provided a simple and effective apparatus for discharging moist air into a room or the like for maintaining or raising the humidity of the atmospheric air therein.

What I claim is:

1. An apparatus of the class described, comprising, an air tank, an air compressor secured on the outer side of said tank for supplying air 55

- therein under pressure, a water receptacle mounted outside of said tank, a nozzle supported without said tank and in communication with the interior of said tank whereby air from said tank is discharged therethrough, a water heating coil within said tank having one end terminating adjacent the discharge end of said nozzle and the opposite end extending within said receptacle, and a heating element within said tank for heating the air therein and the water within said coil whereby to effect a mixture of heated water with the air discharged from said nozzle.
2. An apparatus of the class described, comprising, an air tank, an air compressor secured on the outside of said tank for supplying air therein under pressure, a water receptacle without said tank, a nozzle without said tank and in communication with the interior of said tank, a water heating coil within said tank having an end extending within said receptacle, a siphon tube connected to said coil and having an end disposed adjacent the outlet port of said nozzle, a heating element extending within said tank for heating the air therein and water within said coil whereby to effect a mixture of heated water with air discharged from said nozzle, a water supply for said receptacle, and a valve for controlling said water supply.
3. An apparatus of the class described, comprising, an air tank, an air compressor secured on the outer side of said tank for supplying air therein under pressure, a water receptacle mounted outside of said tank, a nozzle supported without said tank and in communication with the interior of said tank whereby air from said tank is discharged therethrough, a water heating coil within said tank having one end terminating adjacent the discharge end of said nozzle and the opposite end extending within said receptacle,

tacle, a heating element within said tank for heating the air therein and the water within said coil whereby to effect a mixture of heated water with the air discharged from said nozzle, and a motor mounted on said tank for operating said compressor.

4. An apparatus of the class described, comprising, an air tank, an air compressor secured on the outside of said tank for supplying air therein under pressure, a water receptacle without said tank, a nozzle without said tank and in communication with the interior of said tank, a water heating coil within said tank having an end extending within said receptacle, a siphon tube connected to said coil and having an end disposed adjacent the outlet port of said nozzle, a heating element extending within said tank for heating the air therein and water within said coil whereby to effect a mixture of heated water with air discharged from said nozzle, a water supply for said receptacle, a valve for controlling said water supply, and a motor mounted on said tank for operating said compressor.

5. An apparatus of the class described, comprising, an air tank, an air source communicating with said tank for supplying air therein under pressure, a water source connected to said tank, a nozzle supported without said tank and in communication with said tank whereby air from the latter is discharged therethrough, a water heating coil within said tank and having one end terminating adjacent the discharge end of said nozzle and the opposite end communicating with said water source, and a heating element within said tank for heating the air therein and the water within said coil whereby to effect a mixture of heated water with the air discharged from said nozzle.

GUY L. BRIGGS.
